UNITED STATES PATENT OFFICE.

CHARLES C. ROBERTS, OF ANSONIA, CONNECTICUT.

DRIVER FOR DRILL-SOCKETS.

SPECIFICATION forming part of Letters Patent No. 727,450, dated May 5, 1903.

Application filed August 11, 1902. Serial No. 119,348. (No model.)

To all whom it may concern:

Be it known that I, CHARLES C. ROBERTS, a citizen of the United States, residing at Ansonia, in the county of New Haven and State 5 of Connecticut, have invented new and useful Improvements in Drivers for Drill-Sockets, of which the following is a specification.

This invention relates to a driver for drill-sockets; and the object of the invention is to 10 provide a simple article of this character which can be easily and inexpensively made and which can be readily and quickly applied to a drill-socket and which when in working position firmly holds the drill in place.

Ordinarily friction between the drill and its socket is depended upon to drive the former, and when there is much of a strain on the drill the latter turns in its socket, and thereby tears the tail off the drill and also 15 spoils the socket. With my driver, however, these difficulties are wholly overcome. Said driver in the present case is in the form of a sleeve to fit the forward end of the drill-socket, and said sleeve has a projecting portion which 20 extends beyond said forward end, provided with inwardly-projecting fingers adapted to enter the twist of the drill. Said sleeve is adapted to be threaded onto the drill-socket, and when the sleeve is in place, with the fin- 25 gers thereon in the twist of the drill, it will be evident that not only is the drill properly secured in place, but should the same turn it will be drawn farther into the socket by the driver. By virtue of the latter I am enabled 30 to employ drills which have been discarded after injury in the use in the ordinary way to 35 which I have alluded.

The invention is clearly illustrated in the accompanying drawings, forming a part of 40 this specification, and in which—

Figure 1 is a sectional elevation of a drill-chuck and drill and driver, showing the manner of using the latter. Fig. 2 is a side elevation of the driver. Fig. 3 is a face view of 45 the same.

Like characters refer to like parts in all the figures.

In Fig. 1 of the drawings the numeral 5 indicates a drill-socket, having at its forward 50 end the usual socket proper for the reception of the shank of the drill 6. These two implements are of the kind in common use in

metal-work. The forward end of the drill-socket is externally threaded, as at 7, to receive corresponding threads upon the inside 55 of the driver 8, which, it will be seen, is in the form of a sleeve or ring. The said driver 8 has upon its periphery, at diametrically opposite sides thereof, the flat faces 9 to receive the jaws of a wrench to thereby facilitate 60 the application of the driver to the socket. The sleeve therefore presents a polygonal periphery.

The driver 8 has fixed projections 10, which extend forwardly beyond the forward end of 65 the drill-socket and terminate in inwardly-extending fingers 11. These fingers 11 are adapted to engage in the twist or groove of the drill at diametrically opposite places near the shank thereof, as shown in Fig. 1. 70

By virtue of the driver constructed as set forth if the drill should turn during its action upon the work the walls of the groove or twist thereof by engaging the fingers 11 will 75 rotate the driver on the socket, and by reason of the screw-threaded connection between the last-mentioned parts the driver will be moved farther onto the socket, and thereby draw the drill into the socket proper, so that neither the drill nor the socket can be injured. 80

By means of the driver I can employ drills that have been discarded as useless after injury in the old way of operating the same.

The driver may be made of any suitable 85 material and need not be of the exact construction hereinbefore described in detail, for as to this point it may be varied within the scope of my claims.

I usually make the sleeve 8 and the projections 10 and fingers 11 integral; but this, of course, is not essential.

Having described the invention, I claim—

1. A driver for a drill-socket consisting of a sleeve adapted to surround said drill-socket 95 and having a fixed portion adapted to project beyond said drill-socket and said projecting fixed portion having inwardly-disposed fingers adapted to enter the twist or groove of a drill. 100

2. A driver for a drill-socket consisting of an internally-threaded sleeve, the threads of which are adapted to engage corresponding threads upon the exterior of said drill-socket

- and having a portion adapted to project beyond said drill-socket and said projecting portion having inwardly-disposed fingers adapted to enter the twist or groove of a drill.
- 5 3. A driver for a drill-socket consisting of an internally-threaded sleeve the threads of which are adapted to engage corresponding threads upon the exterior of said drill-socket and having a portion adapted to project beyond said drill-socket and said projecting por-
- tion having inwardly-disposed fingers adapted to enter the twist or groove of a drill, and said sleeve having a polygonal periphery.
- In testimony whereof I have hereunto set my hand in presence of two subscribing witnesses.
- CHARLES C. ROBERTS.
